CENTER CUT SHEAR

Francis L. McGary and Charles E. McGary,
Hartensburg, Ky.

Application October 3, 1944, Serial No. 556,967

11 Claims. (Cl. 30—258)

1

The invention relates to a center cut shear, of the type used in cutting sheet metal, and it is an object of the invention to provide an implement by means of which it is made possible to punch a hole in a sheet of metal and then cut in any direction desired, with any desired changes in direction of cut, or to cut off down spouting, to cut off sheet metal pipe of all types and in any shape, and in general to provide a shear of great versatility as compared with shears such as heretofore known.

Another object of the invention is to provide a shear with improved handles for effective grip by the user and which are so arranged as to require a minimum of exertion on his part, yet to produce a maximum result.

Another object is to provide a short, compact shear that will take up but little space, and one that has few parts and few points of wear.

Another object is to provide a shear that is particularly suited to enter the wall of a building constructed of sheet metal, and to make incisions therein, as for windows and the like.

Referring now to the drawings, which are made a part of this application and in which similar parts are indicated by similar reference characters:

Fig. 1 is a side elevation of a preferred form of the invention,

Fig. 2, a top plan of the same, and

Fig. 3, a bottom plan.

In the drawings, reference character 10 indicates a shear member having parallel cutting edges at its forward end and having at opposite sides thereof blades 11, 11' coacting with said cutting edges, said blades being pivoted to the handle 10 at 12. The blades 11, 11' are turned upward at the rear of the pivot 12 and a handle 13 is pivotally connected to them at 14. A link 15, pivotally connected at 16 to the upper handle and at 17 to the lower one, serves to provide a sort of toggle-like action for the operation of the shear.

The upper side edges of the forward portion of shear member 10 at opposite sides of its flat upper face are formed as cutting edges 18, 18', as above stated, to coact with the corresponding inner edges of the respective shear blades 11, 11', the under faces of the blades being inclined upwardly toward their outward edges, as shown in Fig. 1. At the under side of the forward portion of the member 10 there are formed oppositely inclined faces 19' so that the end part is approximately V-shaped in section, and the said end tapers gradually to a point at 19. Preferably the

2

angle formed by each face 19' with the adjacent flat side face of the blade grows steeper toward the point 19, the three faces thus forming an elongated tapered point.

5 This sharp point enables the user to stab the end of the tool through sheet metal and the like. A narrow strip is cut out of the sheet between the blades 11, 11', and this aids in cutting in other than straight lines through a piece of work, since 10 this strip can readily be bent out of the way of the blades, so that almost any desired shapes can be cut out of metal sheets, sheet metal spouting, and the like.

At the grip end of handle 13 the handgrip portion is bent to the left (looking backward along the tool in Fig. 2 from the point 19) away from the median plane passing through the two handles and perpendicular to their pivots, and then is bent back again so that the extreme outer corner, as at 21, lies approximately in the same plane as the righthand face of the main or body portion of said handle and the grip portion lies mainly at the left of the median plane in Fig. 2. The grip portion is also twisted so as to turn the 25 same about the axis of said handle and to throw the bottom member 22 of the grip outward with relation to the upper member 23, thereby to accommodate the grip most effectively to the thumb of the user.

30 The grip portion of the handle 10 is also offset laterally with respect to its body portion, and is bowed outwardly so that substantially all of the parts 24, 25 lies at the right of the median line or plane of the shear in Fig. 2 and, in fact, at 35 the right of a plane passing through the righthand face of the body portion of the handle 10. Preferably a swell is provided at 26 on the working face of grip member 25 to fit the fingers, and a hole 27 is provided in advance of the main finger opening, whereby the forefinger of the user may fit conveniently and comfortably into said hole. This opening for the forefinger is useful 40 in providing convenient means for control of the shear when the hand is relaxed, as in pushing 45 the shear forward after a stroke to locate it for another stroke, and for other like operations. The hole is formed in or just back of the straight portion of the handle. In some shears the forefinger lies in front of the grip since the finger hole is too small to contain all of the fingers, and when in that location is conveniently employed 50 for pulling the shear back from the work, but not for pushing the shear forward toward the work to take another bite.

55 By reason of the offset arrangement of the grip

portions of the tool handles the working surfaces of the grip portions are caused to lie in proper relation to those areas of the fingers and thumb where the greatest application of force naturally falls, and therefore the tool can be used with maximum effectiveness and with minimum exertion on the part of the user. The arrangement of the rocking link, with the pivot of the link close to that of the handle and the movable blades 11, 11, and so located that the line through points 14, 16 and 17 straightens as the tool closes, also makes for easy and effective operation of the tool.

It will be obvious to those skilled in the art that many changes may be made in the device herein disclosed, all without departing from the spirit of the invention; and therefore we do not limit ourselves to what is shown in the drawings and described in the specification, but only as indicated in the appended claims.

Having thus fully described our invention, what we claim is:

1. A shear comprising a center blade, a pivot thereon, a pair of blades on said pivot and located respectively at opposite sides of the center blade, a handle rigid with said center blade, a handle pivoted to the blades of said pair above and rearwardly of said pivot, a link pivoted to said second-named handle rearwardly of its pivotal connection to said blades, and a pivot for said link on said first-named handle rearwardly of and below its pivot on the second-named handle.

2. A shear comprising a blade, a handle rigid therewith, a blade pivoted to said handle, a handle pivoted to the second-named blade above and rearwardly of the pivotal connection of the blade to the first-named handle, and a link connecting said handles, said link being pivoted to the second-named handle rearwardly from the pivotal connection between the handle and said second-named blade and being pivoted to the first-named handle rearwardly of and below its pivot to the second handle.

3. A shear having a blade provided with flat parallel side faces and a flat upper face, said blade also having inclined flat faces intersecting the upper flat face to provide therewith a tapering point, said inclined faces meeting at the bottom of the blade to form a cutting edge gradually increasing in obtuseness and in distance from said flat upper face, and a blade coacting with the first-named blade.

4. A shear as in claim 3, the front end of said flat face being V-shaped, and coacting blades at opposite sides of the first-named blade, said coacting blades terminating approximately at the base of said V-shaped portion.

5. A shear comprising a blade having a flat upper face at its forward end with the cutting edges at the sides of said face, and having oppositely beveled flat faces below said cutting edges, the bevels on said faces meeting at the bottom of the jaw to form a cutting edge and the jaw tapering to a point, said jaw being triangular in section and increasing progressively in depth back of said point to form a cutting edge coacting with

the pointed front end of the shear to punch holes in sheet metal and the like.

6. A shear as in claim 5, the angle formed between the flat upper face and the beveled faces decreasing as they approach the front end of the shear so as to provide an elongated sharp point of very gradually increasing cross section toward the rear of the blade.

7. A shear as in claim 5, including a blade at each side of the first-named blade, the second-named blades terminating at the forward end of the first-named cutting edges, so that the forward ends of the side jaws can coact with the first-named jaws in punching a hole in sheet-metal or the like.

8. A device as in claim 5, including auxiliary blades at opposite sides of the first-named blade, the auxiliary blades terminating at the forward end of the side cutting edges of the first-named blade, and tapering toward said blade at their forward ends, so as to coact with the point thereof in punching a hole.

9. A shear as in claim 5, including a blade at each side of the first-named blade, the second-named blades being pivoted to the first-named blade rearwardly of the rear end of its lower cutting edge and terminating at the forward end of the first-named cutting edges, so that the forward ends of the side jaws can coact with the first-named jaws in punching a hole in sheet-metal or the like.

10. A shear having a handle member and a blade having a point substantially in line with the body of said member, the blade having a flat upper face and oppositely beveled flat side faces, the bevels of the blade merging at the under side of said blade to form a cutting edge and meeting with said upper face at the end of the blade to form a pointed portion triangular in section extending forwardly from the end of said flat upper face.

11. A device as in claim 10, including a coacting forwardly tapering blade terminating at the rear end of said pointed portion.
